UNITED STATES PATENT OFFICE.

JOHN ALFRED GUNN, OF BOSTON, MASSACHUSETTS, AND JAMES EDWARD COSTILO, OF NEW YORK, N. Y.

MAIL-BOX.

SPECIFICATION forming part of Letters Patent No. 651,165, dated June 5, 1900.

Application filed June 24, 1899. Serial No. 721,701. (No model.)

To all whom it may concern:

Be it known that we, JOHN ALFRED GUNN, a resident of Boston, in the county of Suffolk and State of Massachusetts, and JAMES EDWARD COSTILO, a resident of New York, borough of Brooklyn, and State of New York, citizens of the United States, have invented certain new and useful Improvements in Mail-Boxes, of which the following is a specification.

This invention relates to mail-boxes, the object being to produce a simple and cheap receptacle for mail-matter which, while providing a reasonable degree of security for said matter, shall be adapted to dispense with keys and locks directly attached thereto and also be as convenient of access to the mail-carriers as to the occupants of the house or room to which the box is attached.

In carrying out our invention we employ, in combination with an ordinary window-sash, a box having the usual aperture at or near the top thereof, through which mail may be inserted, but not easily removed, and another aperture through the bottom thereof, said aperture preferably being normally closed by a hinged flap or cover. This box is adapted to be screwed or otherwise securely fastened to the window-sash, with its lower end substantially flush with the lower edge of said sash, the arrangement being such that access to the inside of the box may be had only when said window is open, the opening through the bottom referred to being completely covered by the sill when the window is down or closed.

Referring to the drawings, Figure 1 is a front elevation of our improved mail-box. Fig. 2 is a rear elevation of the same. Fig. 3 is a section on line 10 10 of Fig. 1. Fig. 4 is a sectional view showing the box attached to a vertically-sliding window-sash, the box being provided with a hinged cover over the bottom aperture; and Fig. 5 is a similar view showing the sash raised.

Referring by letter to the drawings, particularly to Figs. 4 and 5, which show the preferred form of our invention, A represents the frame of a window, B the window-sash, and C a box secured to the outside of said sash and adapted to be raised and lowered

therewith, the bottom edges of said box resting on the sill D when said window is closed.

Box C, which may be made of any suitable material and of any preferred shape and dimensions, is provided at the top with a narrow opening c for the reception of mail-matter and an opening c' at the bottom thereof, provided with a hinged flap or cover c², normally held in closed position by the spring c³. Ears c⁴ c⁴ c⁴ afford means for securing the box to the sash, the box preferably being located at one side of the window in order that it may be fastened to a side strip, as well as the bottom strip, of the sash for the sake of better security. The box is also provided on the inner surface of the front wall with a deflector or deflecting-ribs c⁵ c⁵.

It is understood, of course, that the window-sash will be provided with the usual locking device, so that when said window is down and locked the box will be locked also and its contents accessible only to one having access to the lock of the window. When the window is raised, the box and contents will be raised also, the spring c³ being stiff enough to support a reasonable amount of mail-matter. On reaching a suitable height the flap c² will be depressed by the fingers, whereupon the contents of the box will be directed toward the inside of the room by the deflector or ribs c⁵. If desired, the flaps c² may be dispensed with, the box being left entirely bottomless, as indicated in Figs. 1, 2, and 3.

We claim—

1. A mail-box having an aperture for the reception of mail-matter and an aperture through the bottom thereof for the discharge of such matter, said box being adapted to be secured to the outside of a vertically-moving window-sash with its lower end substantially flush with the lower edge of the sash whereby the discharge-opening therein will be closed by the sill when the sash is down, and a deflector adjacent to the lower aperture arranged so that when the sash is raised the contents of the box will be directed through the window-opening.

2. A mail-box having an aperture for the reception of mail-matter, an aperture at the bottom thereof for the discharge of such mat-

ter, deflecting-ribs on the inner surface of the front wall of said box, a cover closing the aforesaid bottom aperture and hinged to the lower edge of the said front wall, and a spring 5 adapted to hold the cover normally in closed position, the box itself being adapted to be secured to the outside of a window-sash or other movable partition in such manner that when said sash is closed the bottom edges of 10 the box will be in such close proximity to the sill or other fixed body that access to the inside of the box or the aforesaid cover will be prevented.

3. A mail-box having an aperture for the 15 reception of mail-matter, an aperture at the bottom thereof for the discharge of such matter, the said box being adapted to be secured to the outside of a window-sash or other mov-

able partition in such manner that the bottom aperture will be closed by the sill or other 20 fixed body when the sash is closed, a hinged cover for said bottom aperture, and a spring normally holding the same in closed position, the said cover being hinged to the front wall of the box and therefore adapted when opened 25 to deflect the contents of the box toward the inside of the room.

Signed at New York, borough of Manhattan, and State of New York, this 8th day of June, A. D. 1899.

JOHN ALFRED GUNN.
JAMES EDWARD COSTILO.
